[57] CLAIM

The ornamental design for a utility pole cover, as shown and
described.

DESCRIPTION

FIG. 1 is a perspective top frontal view of a utility pole cover in accordance with my new design;
FIG. 2 is a top plan view thereof;
FIG. 3 is a side elevation view thereof, the opposite side elevation view being identical to the view shown;
FIG. 4 is a perspective bottom frontal view thereof; and,
FIG. 5 is a bottom plan view thereof.
